US00D569107S

(12) **United States Design Patent** (10) Patent No.: **US D569,107 S**
Cotnoir et al. (45) Date of Patent: **** May 20, 2008**

(54) **BIOMETRIC CLEANING BRUSH**

(75) Inventors: **Gary Arthur Cotnoir**, Enfield, CT (US); **Eric Roland Vogel**, Southwick, MA (US)

(73) Assignee: **Accu-Time Systems, Inc.**, Ellington, CT (US)

(**) Term: **14 Years**

(21) Appl. No.: **29/240,216**

(22) Filed: **Oct. 11, 2005**

(51) LOC (8) Cl. **04-01**

(52) U.S. Cl. **D4/119; D4/132**

(58) Field of Classification Search **D4/119, D4/120, 132, 135, 138; 15/106, 143.1, 159.1, 15/160, 186, 187**

See application file for complete search history.

(57) **CLAIM**

The ornamental design for a biometric cleaning brush, as shown and described.

DESCRIPTION

FIG. 1 is a side perspective view of the biometric cleaning brush according to our invention;

FIG. 2 is a side elevation view, the other side being the mirror image;

FIG. 3 is an elevation view from the right side of FIG. 2;

FIG. 4 is an elevation view from the left side of FIG. 2;

FIG. 5 is a top plan view of FIG. 2; and,

FIG. 6 is a bottom plan view of FIG. 2.

The individual strands that make up the bristle structures are partially shown for ease of illustration.
